NET FOR SCOOPING FISH

Yoshio Hirooka, 145, 1-chome, Kyomachibori,
Nishiku, Osaka, Japan

Filed Feb. 11, 1972, Ser. No. 225,708

Term of patent 3½ years

Int. Cl. D22—05

U.S. Cl. D22—22

FIG. 1 is a perspective view of a net for scooping fish in accordance with the present invention;

FIG. 2 is a top plan view thereof;

FIG. 3 is a one end elevational view thereof;

FIG. 4 is a side elevational view thereof;

FIG. 5 is another end elevational view thereof; and

FIG. 6 is a bottom plan view thereof.

The holes appearing in FIGS. 1, 2, 3, 4 and 5 of the drawing are continuous across the design.

I claim:

The ornamental design for a net for scooping fish, substantially as shown and described.

No references cited.
